US00D934130S

(12) **United States Design Patent** (10) Patent No.: **US D934,130 S**
(45) Date of Patent: **** Oct. 26, 2021**

(54) **VEHICLE BUMPER COVER**

- (71) Applicant: **VOLKSWAGEN AKTIENGESELLSCHAFT, Wolfsburg (DE)**
- (72) Inventor: **Felipe Montoya Bueloni, Wolfsburg (DE)**
- (73) Assignee: **VOLKSWAGEN AKTIENGESELLSCHAFT, Wolfsburg (DE)**
- (**) Term: **15 Years**
- (21) Appl. No.: **29/733,058**
- (22) Filed: **Apr. 29, 2020**

(30) **Foreign Application Priority Data**

- Nov. 8, 2019 (WO) WIPO89176

(57) **CLAIM**

The ornamental design for a vehicle bumper cover, as shown and described.

DESCRIPTION

FIG. 1 is a front view of the vehicle bumper cover of the present invention;

FIG. 2 is a front and right side perspective view thereof;

FIG. 3 is a front and left side perspective view thereof;

FIG. 4 is a right side view thereof;

FIG. 5 is a left side view thereof;

FIG. 6 is a rear view thereof;

FIG. 7 is a rear and left side perspective view thereof;

FIG. 8 is a rear and right side perspective view thereof;

FIG. 9 is a top view thereof; and,

FIG. 10 is a bottom view thereof.

1 Claim, 5 Drawing Sheets
